Primary Examiner — Ricky Pham(74) *Attorney, Agent, or Firm* — Millen, White, Zelano, Branigan, P.C.(57) **CLAIM**

The ornamental design for index steel chopping boards, as shown and described.

DESCRIPTION

FIG. 1 is a top perspective view of the index steel chopping boards showing my new design; and,

FIG. 2 is a side perspective view thereof.

The portions of the index steel chopping boards not shown in the originally filed drawings are not included in the claims.
